UNITED STATES PATENT OFFICE.

ALBERT KLUG, OF COLUMBUS, NEBRASKA.

PLOWPOINT.

Application filed April 8, 1925. Serial No. 21,668.

This invention relates to improvements in plow points and has for an object the provision of a simple, strong and durable point which may be secured over a worn or otherwise useless plow point, the construction providing means whereby the old point may be renewed and the plowshare reinforced.

With the above and other objects in view, the invention further includes the following novel features and details of construction, to be hereinafter more fully described, illustrated in the accompanying drawings and pointed out in the appended claim.

In the drawings:—

Figure 1 is a top plan view showing a plowshare equipped with a plow point constituting the present invention.

Figure 2 is a section on the line 2—2 of Figure 1.

Figure 3 is a plan view of the blank from which the plow point is made.

Figure 4 is a perspective view showing the point after being bent into shape.

Figures 5 and 6 are sections taken respectively on the lines 5—5 and 6—6 of Figure 3.

Referring to the drawings in detail wherein like characters of reference denote corresponding parts, the reference character 10 indicates an ordinary plowshare, the point 11 of which has become worn.

The plow point constituting the present invention is formed from a single blank of material indicated at 12 in Figure 3 of the drawings. This blank is of elongated sub-

stantially triangular shape and is bent transversely along the dotted lines indicated at a

so as to provide an upper portion 13 and a lower portion 14 whose forward edges are connected as indicated at 15. A substantially V-shaped member is provided which is 40 welded or otherwise secured over the point 11 of the plowshare so as to extend beyond the worn point and provide a new or renewed point. The edges 16 and 17 of the point are preferably tapered as shown in 45 Figures 5 and 6 of the drawings.

In addition to renewing the plow point, the invention provides a reinforcing means for the plow which, after the plow point has become worn and thin frequently breaks at 50 the point indicated at b in Figure 1 of the drawings.

The invention is susceptible of various changes in its form, proportions and minor details of construction and the right is 55 herein reserved to make such changes as properly fall within the scope of the appended claim.

Having described the invention what is claimed is:—

A plow point of the character described comprising a blank of elongated substantially triangular shape bent transversely adjacent the smaller end thereof to provide an upper and a lower portion disposed at an 65 oblique angle relative to each other to form a substantially V-shaped member and the opposed edges of the large portion of said blank being tapered as and for the purpose specified. 70

In testimony whereof I affix my signature.
ALBERT KLUG.
